UNITED STATES PATENT OFFICE

JOHN S. LITTLEFORD, JR., OF FORT THOMAS, KENTUCKY

ROAD MARKER

Application filed February 27, 1928, Serial No. 257,463. Renewed July 15, 1931.

My invention relates to improvements in road marking apparatus. One of its objects is to provide an improved road marker adapted to be manually propelled or power driven as may be desired. Another object is to provide a resilient and adjustable tension of the marker wheel upon the road surface independent of the propelling or guiding means. Another object is to relieve the handle bars or other propelling means from vibration or shock due to the marker wheel passing over uneven road surfaces. Another object is to provide for producing a mark of uniform strength or density upon the road irrespective of the amount or head of paint in the paint reservoir or any inequalities in the road surface. Another object is to prevent the feed or drip of the marking fluid when the marking wheel is out of contact with the road surface. Another object is to provide improved means to feed and distribute the marking fluid uniformly over the face of the marking wheel irrespective of variation in the viscosity or other qualities of the marking fluid employed. Another object is to provide improved means adapted to be conveniently shifted from idle to operative position and adapted to sweep the road surface in advance of the marker wheel. Another object is to provide an improved truck or supporting structure, and improved adjustable means to guide the truck and marking wheel and to variably tension the marker wheel relative to the truck. My invention also comprises certain details of form and arrangement and combination of components, all of which will be fully set forth in the description of the accompanying drawings, in which:

Fig. 1 is a side elevation of a road marking apparatus arranged for manual propulsion and guidance, embodying my improvements.

Fig. 2 is a plan view of the same.

Fig. 3 is a sectional detail through the axis of the marker wheel, taken on line 3-3 of Fig. 2.

Fig. 4 is a sectional detail taken on line 4-4 of Fig. 1.

Fig. 5 is an enlarged side elevation of the road sweeper and its driving mechanism.

Fig. 6 is an enlarged sectional detail taken on line 6-6 of Fig. 2.

Fig. 7 is a detail of the mechanism employed to spread and feed the marking fluid to the marker wheel.

The accompanying drawings illustrate one embodiment of my invention in which 15 represents the frame or truck upon which the 60 marker wheel 16 is journaled by means of an axle 17. The truck 15 is provided with journal boxes in rear of the journals for the axle 17 to support a truck axle 18, which axle 18 is supported upon the road surface by means 65 of truck wheels 19. The truck wheels 19 are uniformly in contact with the road surface and serve to support the weight of the truck. The marker wheel is in contact with the road surface when marking the road and is out of 70 contact with the road surface except when employed to mark the road, which is effected by tilting the truck upon the axle 18 and wheels 19 so as to elevate the marker wheel out of contact with the road. Marker wheels of 75 different widths are designed to be interchanged upon the axle 17.

A supplemental truck member 20 is provided with journal bearings 21 in which the axle 18 is journaled, thereby hinging the 80 truck member 20 to the truck 15 upon the axle 18 as a hinge pin or axle. As shown in Fig. 6, the relative hinge movement of the truck members 15 and 20 is limited by means of a bolt 22, passing through the web of truck 85 member 20 and also through the web 73 of the truck member 15, a tension spring 72 encircles the bolt 22 between the webs of the truck members 15 and 20 and a tensioning spring 23 is interposed between the web 73 and an 90 adjustable nut 24. The truck member 20 detachably supports a tank 25 in which is stored a body of marking fluid, white paint for instance. A pair of handle bars 26 are 95 adjustably mounted upon the truck member 20, and enable an operator to guide the truck and marker wheel wherever desired. By shifting the handle bars to different positions of inclination in a horizontal plane, the operator is enabled to walk at either side of the 100

freshly laid mark, or to straddle the mark if desired, depending upon whether it is a straight or curved mark. Also by elevating or depressing the handle bars the marker wheel may be adjusted into contact with the road surface or elevated above and out of contact with the road surface. When the handle bars are in position to cause the marker wheel to contact with the road surface, a limited amount of tension is placed upon the springs 72 and 23, which creates a resilient tension upon the marker wheel independently of movement of the handle bars, tending to cause the marker wheel to automatically follow the inequalities of the road surface and to apply an even and uniform coating of paint upon the low as well as the high points of the road surface without requiring constant attention and adjustment of the marker wheel through the handle bars. The tension of the springs 72 and 23 interposed between the handle bars and the marker wheel relieves the handle bars and the wrists of the operator from vibrations and shocks due to inequalities in the road surface.

In order to conveniently interchange marker wheels upon the axle 17, I preferably provide a sleeve 64 upon the axle 17 intermediate of the arms of the truck member 15. A marker wheel of any desired width of face is slipped loosely over the sleeve 64, and the sprocket wheel 27 slipped onto the sleeve 64 adjacent to the hub of the marker wheel. The hub of the sprocket wheel 27 is provided with a clutch pin 62 which enters a recess in the hub of the marker wheel so as to clutch the sprocket wheel and marker wheel together. A set screw 63 serves to lock the marker wheel, sprocket wheel, and sleeve to the axle 17, or if desired to lock the marker wheel, sprocket wheel, and sleeve together allowing the sleeve to rotate on the axle 17. A cross pin 65 enables the axle 17 and marker wheel to be turned by hand when cleaning the paint from the marker wheel. By withdrawing the axle 17 endwise from the sleeve 64, the marker wheel may readily be removed and replaced with a marker wheel of a different width of face. The spur gear 27 drives a pinion 28 upon a shaft 29 which actuates a small pump 30 whenever the marker wheel is rotated by reason of being in contact at its periphery with the road surface. A flexible tube 31 leads from the supply tank 25 to the pump 30, and a conduit 32, preferably supplied with a cut-off and regulating valve 33, serves to deliver the paint or other marking fluid through the exit end 34 of the conduit 32 upon the central and upper portion of the marker wheel. The exit end 34 is made the highest point in the conduit 32 so that the instant that the marker wheel is lifted from contact with the road surface and the pump ceases to rotate, all flow or even drip of marking fluid at the exit 34 ceases. The exit

34 is also preferably higher than the level of the marking fluid in the tank 25, which insures that the fluid will not leak past the pump so as to drip at the exit 34.

The viscosity and other physical characteristics of the paint or marking fluid vary from time to time and with changes in the nature of the fluid, and these variations tend to materially affect the regulation and distribution of the marking fluid upon and uniformly over the face of the marker wheel. In order to insure such regulation and distribution irrespective of variations in the marking fluid, I provide a roller 35 of sufficient weight to bear upon the face of the marker wheel and force the marking fluid laterally from the center of the marker wheel where it is delivered from the exit 34 in both directions toward the edges of the marker wheel until the fluid is evenly and uniformly distributed entirely across the face of the marker wheel from one edge to the other thereof. By providing properly proportioned helical or annular grooves 36 in the face of the roller 35, said grooves serve to meter and distribute the marking fluid as a series of closely spaced parallel circumferential lines or ribs of marking fluid upon the face of the marker wheel which later spread out and merge one with another to form a substantially uniform sheet or coating over the face of the marker wheel where said wheel contacts with the road surface, and thereby provides a mark of uniform width and even density. The roller 35 is journaled in the free ends of two links or arms 37, which are pivotally attached at 38 to the truck frame 15. The weight of the roller 35 holds it in place upon the marker wheel. The roller 35 may be thrown back out of engagement with the marker wheel if desired. The marker wheel is provided with a soft rubber tire 40 over which is drawn a canvas facing 41, which is secured in place by means of draw strings 42.

A sweeper drum or cylinder 43 is mounted upon an axle 48 upon which axle are loosely journaled supporting wheels 57 and 58. The axle 48 is journaled at opposite ends to the free ends of arms or links 44, which are pivotally attached at 45 to the truck member 15. In its full line position Fig. 1 the sweeper drum rests in front of the marker wheel upon the road surface and is driven in a direction the reverse to that of its progress along the road by means of a chain belt 46, strained over a sprocket wheel 47 on the axle 48 and over a sprocket wheel 50 on a stud shaft 51, which shaft 51 is attached to one of the arms 44. The hub of the sprocket wheel 47 carries a pinion 52 which meshes with and is driven by the gear 27 when the sweeper is in full line position. The sweeper is adapted to be thrown to an idle position shown in dotted line Fig. 1 in which the pinion 52 is out of

mesh with the gear 27, and the sweeper is idle.

When it is desired to attach the marker to a truck or other power driven vehicle, the 5 truck member 20 and tank 25 are detached from the truck member 15 and axle 18, and a bracket member attached to the running board or other part of the power driven vehicle takes the place of the truck member 10 20, and is provided with a bolt 22, spring 23 and nut 24, similar to those shown in Fig. 6, whereby the marker wheel may be yielding- 15 tensioned relative to its propelling member. The tank 25 may then be set upon the truck and connected by its conduit 31 with the pump 30. A hand lever attached to the frame 15 and operated by an operator carried on the truck serves to lift the marker wheel from the road surface whenever required.

20 The apparatus herein shown and described is capable of considerable modification within the scope of the claims without departing from the spirit of my invention.

What I claim is:

25 1. A road marker comprising a truck member, a truck supporting axle having wheels to support said truck member, a marker wheel supported upon said truck and adapted by rocking said truck upon its supporting 30 axle to be engaged with and disengaged from the road surface, a propelling member hinged upon said truck supporting axle and means interposed between said propelling member and said marker wheel to yieldingly tension the application of the marker wheel 35 to the road surface.

2. A road marker comprising a truck axle having supporting wheels in engagement with the road surface, a truck member mounted 40 upon and adapted to be rocked upon said axle, a marker wheel adapted to be engaged with and disengaged from the road surface by rocking said truck member upon said axle, a truck propelling member, and means inter- 45 posed between said propelling member and said marker wheel to apply yielding tension to said marker wheel to cause the marker wheel to follow inequalities in the road.

3. A road marker comprising a truck axle 50 having supporting wheels in engagement with the road surface, a main truck member forward of said axle and adapted to be rocked upon said axle, a marker wheel journaled to said main truck member, an auxiliary truck member through which energy to propel said truck is applied, hinged to said truck axle, resilient tensioning means interposed between 55 said main and auxiliary truck members and adapted to yieldingly hold the marker wheel in contact with the road surface.

60 4. A road marker comprising a truck axle having supporting wheels in engagement with the road surface, a main truck member forward of said axle and adapted to be rocked 65 upon said axle, a marker wheel journaled to said main truck member, an auxiliary truck

member through which energy to propel said truck is applied, hinged to said truck axle, resilient tensioning means interposed between said main and auxiliary truck members and adapted to yieldingly hold the marker 70 wheel in contact with the road surface, a marking fluid reservoir mounted upon said auxiliary truck member, a pump driven from said marker wheel and adapted to pump a supply of marker fluid from said reservoir 75 and discharge said fluid through a discharge conduit upon the face of said marker wheel, the exit end of said discharge conduit being above the fluid level in said reservoir and the highest point in said discharge conduit to prevent discharge or drip of the marking fluid when the marker wheel is out of contact with the road surface.

5. A road marker comprising a truck axle 80 having supporting wheels in engagement with the road surface, a main truck member forward of said axle, a marker wheel journaled to said main truck member in advance of said truck axle, a marking fluid reservoir mounted upon said truck, a pump driven 85 from said marker wheel and adapted to pump a supply of marking fluid from said reservoir and discharge said fluid through a discharge conduit upon the face of said marker wheel, the exit end of said discharge 90 conduit being above the fluid level in said reservoir and the highest point in said discharge conduit to prevent discharge or drip of the marking fluid when the marker wheel is out of contact with the road surface. 95

6. A road marker comprising a truck axle 100 having supporting wheels in engagement with the road surface, a main truck member forward of said axle, a marker wheel journaled to said main truck member in advance of said truck axle, a marking fluid reservoir mounted upon said truck, a pump driven from said marker wheel and adapted to 105 pump a supply of marking fluid from said reservoir and discharge said fluid through a discharge conduit upon the face of said marker wheel, the exit end of said discharge conduit being above the fluid level in said reservoir and the highest point in said discharge conduit to prevent discharge or drip of the marking fluid when the marker wheel is out of contact with the road surface. 110

7. A road marker comprising a truck axle 115 having supporting wheels in engagement with the road surface, a main truck member forward of said axle and adapted to be rocked upon said axle, a marker wheel journaled to said main truck member, an auxiliary truck member through which energy to propel said truck is applied, hinged to said truck axle, resilient tensioning means interposed between 120 said main and auxiliary truck members and adapted to yieldingly hold the marker wheel in contact with the road surface, means to feed a supply of marking fluid upon the face of said marker wheel, and a distributing roller in engagement with the face of said marker wheel, said distributing roller being provided with a series of substantially parallel grooves encircling its periphery and serving to spread and meter the supply of marking fluid passing through 125 said grooves and between said roller and marker wheel.

7. A road marker comprising a marker truck, a marker wheel mounted upon said truck and adjustable into and out of engage- 130

ment with the road surface, means to feed a supply of marking fluid upon the face of said marker wheel, a distributing roller in engagement with the face of said marker wheel, said distributing roller being provided with depressions in its periphery serving to feed the marking fluid in measured quantity between said roller and said marker wheel, and to distribute the marking fluid uniformly over the face of said marker wheel.

8. A road marker comprising a marker truck, a marker wheel mounted upon said truck and adjustable into and out of engagement with the road surface, an adjustable supporting frame pivotally mounted upon said truck and adjustable from an idle to an active position, a road sweeping drum journaled to said frame and having an idle and an active position, and driving means operatively connecting said sweeping drum in driving relation with said marker wheel when said sweeping drum is in its active position.

25. 9. A road marker comprising a truck axle having supporting wheels in engagement with the road surface, a main truck member forward of said axle, a marker wheel journaled to said main truck member in advance of said truck axle, a marking fluid reservoir mounted upon said truck, a pair of propelling handle bars mounted upon and extending rearwardly from said truck, said handle bars being respectively adjustable relative to said truck to enable the operator to walk along upon one side of the fresh mark as well as to straddle the mark.

10. A road marker comprising a truck axle having supporting wheels in engagement with the road surface, a truck member adapted to be rocked upon said axle, a marker wheel axle mounted upon said truck member, a sleeve mounted upon said marker-wheel axle, a marker wheel and a pump driving wheel mounted upon said sleeve and clutched one to the other.

11. A road marker comprising a truck axle having supporting wheels in engagement with the road surface, a truck member adapted to be rocked upon said axle, a marker wheel axle mounted upon and removable endwise from said truck member, means to manually rotate said marker wheel axle, a sleeve mounted upon said marker wheel axle, a marker wheel and a pump driving wheel mounted upon said sleeve and clutched one to the other, and means adjustable to lock said marker wheel, driving wheel, and sleeve in driving relation to said marker wheel axle.

12. A road marker comprising a hand propelled truck member, a truck supporting axle having wheels to support said truck member and upon which said truck is adapted to be rocked manually to apply the marker wheel to the roadbed and remove the marker wheel

from contact with the roadbed, a marker wheel journaled upon said truck and adjustable manually into and out of contact with the roadbed by rocking said truck, and means interposed between said truck and marker wheel to yieldingly hold said marker wheel in contact with the roadbed.

In testimony whereof I have affixed my signature.
